CURTAIN STRETCHER

John S. Walker and Alverna M. Walker,
Pittsburgh, Pa.Original application March 29, 1937, Serial No.
133,680. Divided and this application October
3, 1939, Serial No. 297,690

4 Claims. (Cl. 45—24)

This invention relates to curtain stretchers and it has particular relation to a self-squaring stretcher frame adapted to be positioned in various angular positions.

This application is a division of our application filed March 29, 1937; Serial Number 133,680, which matured into Patent No. 2,178,153, issued October 31, 1939.

The primary object of the invention is the provision of curtain stretchers wherein any number of curtains within reason can be conveniently stretched either of the same size or of different sizes, that is to say, with respect to the length thereof and providing such apparatus wherein the frame is disposed at varying angles at the will of the user thereof.

Another object of the invention is to provide a curtain stretcher wherein the frame is so formed that the members of the frame, side and end members, are maintained at right-angles with respect to each other.

Another object of the invention is the provision of an apparatus, which is simple in construction, preferably formed from metal so as to avoid any sagging or bending thereof when in use. Other objects may be inferred from the nature of the invention.

In providing a curtain stretcher in accordance with our invention, the curtain stretcher frame is formed of a pair of side members and a pair of end members secured together with self-squaring corner plates. An upright or vertical support is positioned adjacent each of the end members and these supports are provided with means for pivotally supporting the frame. In addition means are provided for locking the frame in various angular positions. Moreover an apparatus formed in accordance with our invention provides a structure adapted to support two different sizes of curtains, with respect to the length thereof. For a better understanding of the invention, reference may now be made to the accompanying drawings, in which—

Figure 1 is a plan view of a curtain stretcher constructed in accordance with the invention, with the frame disposed in substantially a horizontal plane.

Figure 2 is a side view (elevation) of the invention, showing by full lines one angular adjustment of the frame and by dotted lines several other adjustments thereof.

Figure 3 is a fragmentary front elevation of the invention.

Figure 4 is a fragmentary plan view of one of

the rails of the frame with a portion thereof in section for the sake of clearness.

Figure 5 is a sectional view of the invention taken through one of the side rails of the frame.

Figure 6 is a sectional view of the invention taken through one of the end rails of the frame.

In practicing our invention a curtain stretcher is formed with a pair of vertical supports or uprights 10, each having a hollow base 10a, preferably of cone shape forming a container with a removable plug so that the base may be filled with sand or other material to give weight thereto. However, the base may also be formed flat from solid metal of a weight sufficient for the purpose. Each upright or support is threaded in a collar or the like on the base for connection therewith. Mounted on the uprights or supports 10 is a stretcher frame 11, hereinafter fully described.

The frame 11 is provided with side members or rails 12 and end members or rails 13, each formed from sheet metal bent into a three-sided sheathing. The open portion 14 of each member 12 has secured therein guide elements 16 and 17, respectively, these being reversely angled to each other and the piece 17 creating a channel or pocket 18. Slidably fitted in the guides 16 and 17 for projection at a downward angle from the closed end of the rail 12 toward the open side 14 are stems 19, of curtain hooks 20, these being spaced uniformly throughout the length of the rail 12. Disposed about each stem 19 is a coiled tensioning spring 22 which operates to retract the stem 19 so that normally the pin or hook 20 is confined in the pocket 18, for concealment thereof. The spring 22 permits the pulling of the pins outwardly from the pocket 18 when it is desired to engage a curtain or curtains 23 for the stretching of the same.

The open portion 25 of each member 13 has secured therein guide portions 26 and 27, respectively, the latter portion providing a pocketing space 28 at the open side 25 of the member 13. Slidably fitted with the guides 26 and 27 are stems 29 of curtain pins or hooks 30, each stem being inwardly inclined or reversely set to the pins 19. Disposed about each of the stems 29 is a coiled tensioning spring 32 which acts upon the stem to normally retract the pin 30 into the space or pocket 28 to thus conceal the same when not engaged with the curtain or curtains 23. These pins are readily pulled outwardly for easy engagement with the curtains when the same are to be stretched on the frame 11.

The side rails 12 are superimposed upon the

end rails 13 and positioned between the rail members at their meeting points are self-squaring triangular shaped corner plates 35, each plate having an upstanding flange 36, which engages the outer surface of the side members and a depending flange 37, which engages the outer surface of the end members. It will be noted that the right angular disposition of the flange 36 and 37 square the rails 12 and 13 with relation to each other. The rail members 12 and 13, in their sheathings, are provided with vertically aligned openings or holes 38 which are in longitudinal rows, spaced from each other and selectively accommodate bolt fasteners 39 for adjustably clamping the rails 12 and 13 together with the plates 35 interposed therebetween at the crossing points of the rail members. Each bolt 39 carries a cleat 41, which functions to grip the under side of the end rail 13, and the bolt also is provided with a nut 42 having an upstanding wing grip 43 which provides easy adjustment of the frame. Thus it will be seen that the side and end members can be readily adjusted with relation to each other to increase or decrease the size of the frame for stretching of a curtain or curtains.

The corner plates 35 have fitted therewith curtain pins or hooks 44, which are adapted for corner attachment with the curtains 23 on the initial placement of the latter in the frame; and thereafter the pins or hooks 20 and 30 are engaged with the curtain or curtains at the sides and ends thereof at uniform intervals for sustaining the curtain or curtains in a stretched condition when carried in the frame 11.

On the posts 10 are releasably fitted collars 46, each having a notch 47 opening through its lower edge for accommodating a holding lug 48 formed on the respective posts or supports 10 to hold the collars fixed against rotation on the supports. Each of the collars 46 is provided with a pivot arm 49, for a pivot 50, swingably connecting thereto a bracket 52 riveted or otherwise secured to each end member 13, intermediate the ends thereof. In this manner the frame 11 is vertically swingable between the posts or supports 10 for angular adjustment of such frame. Each collar 46 is specially constructed to slip over the support so that the lug 48 will engage in the notch 47, in the collar, when the same is lowered upon the support. The lugs 48, on the supports, are arranged so that the brackets 52 will hold the stretcher frame approximately at waist line of a person so that the user of the stretcher is not required to bend over for placing of a curtain or curtains on the stretcher frame 11.

Slidably mounted on each support or upright 10 is a collar 53, the collar being provided with a latch or keeper 54 adapted to engage one of the side members 12, with a second latch 56 formed at substantially right angles to the first mentioned latch, the latch 56 engaging an end member 13. As shown in Fig. 3, the latch is fitted about the support 10 to engage both sides and end members for locking the frame in substantially vertical position.

Adjustably engaged with each end member 13, in any of the holes 38, adjacent to the brackets 52 is a pivot bolt 57 having swingingly pivoted thereto an arm 58. Each arm 58 is pivoted at 59 to a coupling 61 secured to each post or support 10. Thus by the use of the pivoted arms 58 the frame 11 can be maintained in a horizontal plane or at any angle thereto at the will

of the operator in the use of the apparatus. The bolts 57 carry nuts 62 similar to the nuts 39.

Positioned crosswise of the frame 11 and engaging the side members 12 is a supplemental 5 or auxiliary stretcher bar 63, which as shown is in the form of a tube but it is to be understood that this bar, in actual practice will be in structure the same as the members 13. The stretcher bar 63 is engaged by clamp hooks 64, these being 10 selectively engageable in the holes 38, in the side members 12, so that the auxiliary bar can be secured to the frame between the end members 13. Within the tube 63 and carried centrally therein by end caps 65 is a rod 67, having loosely connected thereto curtain hooks 68, these moving in slots 69 in the tube 63 and being adapted for attachment to a curtain or curtains at one end thereof. This auxiliary bar 63 is usable with the apparatus for stretching curtains of less length than that carried directly by the frame under the adjusted set of the side and end members 12 and 13, respectively.

From the foregoing description it is apparent that we have provided a curtain stretcher adapted to 25 stretch curtains of two sizes, with respect to the length thereof, at one time without changing the stretcher frame. In addition we have provided a structure which is positively self-squaring, together with a structure adapted to be positioned 30 in various positions and which can be locked in these positions at will of the operator.

It is to be understood that the form of the invention herein shown and described is merely 35 illustrative of the preferred embodiments and that such changes as fall within the purview of one skilled in the art may be made without departing from the spirit of the invention and the scope of the appended claims.

What we claim:

40 1. A curtain stretching apparatus comprising a pair of vertical supports, each of the supports having a lug extending outwardly therefrom adjacent the top thereof, a collar mounted on each of the supports, the collar engaging the lug on 45 the support for securing the collar against rotation, a curtain stretcher frame pivotally mounted to the collars and means having an arm mounted on the supports and engaging the stretcher for locking the stretcher frame in position.

2. A curtain stretching apparatus comprising a pair of vertical supports, each of the supports having a lug extending outwardly therefrom adjacent the top thereof, a collar slidably mounted 55 on each support, the collars engaging the lugs for securing the collars against rotation, an arm extending horizontally from each collar, a curtain stretcher frame pivotally mounted to the arms and means slidably mounted on the supports and engaging the frame for locking the frame in substantially vertical position.

3. A curtain stretching apparatus comprising a pair of weighted supports, each of the supports having a lug extending outwardly therefrom adjacent the top thereof, a collar slidably mounted 65 on each support, the collars engaging the lugs for securing the collars against rotation, an arm extending horizontally from each collar, a curtain stretcher frame pivotally mounted to the arms, between the supports, an arm pivotally mounted on each of the supports, the arm adapted to engage the frame for locking the frame in angular position and means slidably mounted on the supports and engaging the frame for locking 70 the frame in substantially vertical position.

4. A curtain stretching apparatus comprising a pair of supports, each of the supports having a lug extending outwardly therefrom adjacent the top thereof, a notched collar slidably mounted on each support, the notches engaging the lugs for securing the collars against rotation, an arm extending horizontally from each collar, a curtain stretcher frame pivotally mounted to the

5 arms, between the supports, flanged element slidably mounted on the supports for engaging the frame to lock frame in substantially vertical position and means including an arm pivotally mounted on the supports for locking the frame in angular position.
